UNITED STATES PATENT OFFICE.

JOSEPH URBANEK, OF CHICAGO, ILLINOIS.

NON-SKIDDING DEVICE FOR WHEELS.

1,345,291.

Specification of Letters Patent. Patented June 29, 1920.

Application filed December 13, 1918. Serial No. 266,574.

To all whom it may concern:

Be it known that I, JOSEPH URBANEK, a subject of the Emperor of Austria, residing at Chicago, county of Cook, and State of Illinois, have invented certain new and useful Improvements in Non-Skidding Devices for Wheels, of which the following is a specification.

This invention relates to improvements in vehicle wheels and particularly to types adapted to be used in connection with high grade vehicles.

The principal object of the invention is to provide devices in the form of attachments which may be applied to a wheel of the ordinary type of construction, the device being adapted to prevent slipping or skidding of the wheel upon an icy or otherwise slippery surface.

20 A further object is to provide means whereby the non-skidding devices are limitedly movable within their holder so as to present a plurality of spurs adapted to make contact with the surface over which the vehicle wheels travel.

These and other like objects are attained by the novel construction and combination of parts hereinafter described and shown in the accompanying drawings, forming a material part of this disclosure, and in which—

Figure 1 is a side elevational view showing a wheel made in accordance with the invention.

Fig. 2 is a cross-sectional view taken substantially on the line 2—2 of Fig. 3, the cylindrical extension 35, however, being shown in section to expose the interior thereof.

Fig. 3 is a fragmentary side elevational view and sectional view showing the construction of the device.

Referring to the drawings, it will be seen that the wheel, which is of the usual type of construction, comprises a rigid hub 10, secured to the axle in any preferred manner and provided with a plurality of radially extending spokes 11, fixed at their outer ends in the rim 12.

Circumjacent to the felly 12, is a rim 14, having inturned flanged edges 15 adapted to engage with the inner edges 16 of a tread element 17, containing the usual pneumatic tube 18, all of the several parts being of the ordinary type of construction.

55 The invention comprises an annular band 20, having an inwardly flanged edge 21, secured by screws or like fastening means 22

to the felly 12, the band being equivalent in diameter to that of the felly and is formed with a plurality of equally spaced cylindrical projections 24, its front flanged edge 25 extending slightly outward beyond the inturned flanges 15 of the wheel-rim.

This flange 25 is equal in diameter with a ring 26 superposed over the band 20 upon the opposite side, and between the ring 26 and flange 25 is a casing 28 substantially rectangular in cross section, extending outwardly to a point approximately equal with the center of the inner tube 18, forming a continuous chamber around the wheel.

70 Formed at its center are openings 30, in which are slidably engaged stems 31, having upon their outer ends curved transverse elements 32, terminating in projections 33 adapted to engage on the sides of the stems 31 being guided by hollow cylindrical extensions 35, formed with the base of the projections 24.

75 Formed with or secured to the stems, central in their length, are transverse bars 36, having elongated heads 37, the outer edges of the bars having rack teeth 38, and normally pressed outward, due to coiled compression springs 39, the racks engaging with spur pinions 40 rotatably mounted 80 upon spindles 41 secured transversely in the casing 28. The teeth of the pinions mesh with other racks 42, extending laterally outward from plungers 43, having conical spur like heads 44, and guided by projections 45 extending radially-centerward from the outer walls of the casing 28, the normal position of the spurs 32 and 44 being indicated in Fig. 3, or around the periphery of the wheel shown in Fig. 1, except at the lower part thereof, where the showing is such as to indicate the spur 32 having been pressed radially inward against the spring 39, at which time obviously the spur points 44 will be extended outwardly, 90

95 being indicated in Fig. 3, or around the periphery of the wheel shown in Fig. 1, except at the lower part thereof, where the showing is such as to indicate the spur 32 having been pressed radially inward against the spring 39, at which time obviously the spur points 44 will be extended outwardly, 100 due to the action of the rack and pinions intermeshing therebetween.

It will also be clearly evident that the entire device may be readily removed by disconnecting the bolts 22, and removing the rings 20 with the several parts assembled intact.

Having thus described my invention what I claim as new and desire to secure by Letters Patent, is—

110 A device of the class described comprising a peripheral casing attached to the side of

the felly of a wheel, said casing inclosing an annular chamber, a plurality of relatively large and small holes in the outer wall of said casing arranged in spaced apart 5 relation, pointed stems adapted to move radially through said small holes, means for guiding said stems in a radial direction, additional stems adapted to move radially through said large holes, horizontal bars 10 rigid to the outer ends of said last-named stems, fingers on the ends of said bars adapted to embrace the side walls of said casing, bars rigidly attached to said last-named stems at about the midpoint of the 15 latter and at right angles thereto, vertical racks on the ends of said last-named bars,

pinions rotatably mounted in the side walls of said casing and meshing with said racks, extensions on said first-named stems having racks thereon, said last-named racks also 20 meshing with said pinions, pockets formed in the inner walls of said casing radially adjacent each of said last-named stems, means rigid to said pockets for guiding said last-named stems, coiled springs surrounding 25 said stems between said last-named bars and the innermost points of said pockets, and means for attaching said casing to the felly of a wheel.

In testimony whereof I have affixed my 30 signature.

JOSEPH URBANEK.
